CLAIM

The ornamental design for a corneal flap cover with eye ring, as shown and described.

DESCRIPTION

FIG. 1 is a perspective view of a corneal flap cover with eye ring showing my new design;

FIG. 2 is a top plan view of the corneal flap cover with eye ring illustrated in FIG. 1, the bottom view being a mirror image thereof;

FIG. 3 is a front elevational view thereof, the rear elevational view being a mirror image of the front view;

FIG. 4 is an end view thereof as seen from the left side; and, FIG. 5 is an end view thereof as seen from the right side.

The broken line showing in FIG. 1 is for illustrative purposes only and is not part of the claimed design.
